UNITED STATES PATENT OFFICE.

JULIUS A. SCHWEIG, OF ST. LOUIS, MISSOURI.

LOCK FOR ELEVATOR DOORS.

Application filed October 1, 1926. Serial No. 138,886.

This invention relates to locks for elevator doors. One of the principal objects of the invention is to devise a cheap and efficient lock which will prevent the opening of the elevator doors when the car is not at a landing and which will prevent the operation of the elevator until all the doors in the shaft are closed and locked. Another object is to prevent the lock from being tampered with when the door is open. Other objects are simplicity of construction, ease of assembly and installation, and compactness and economy of design. The invention consists in the combinations and arrangements of parts hereinafter described and claimed.

In the accompanying drawings which form part of this specification and wherein like symbols refer to like parts wherever they occur,

Fig. 1 is an interior view of a portion of an elevator shaft at one of the door openings, showing a locking device embodying my invention mounted in the shaft in position to cooperate with the latch bar of a vertical sliding door;

Fig. 2 is an enlarged face view of the lock and the parts associated therewith, the cover plate of the lock being shown removed and the lock being shown in locked position;

Fig. 3 is a view similar to Fig. 2, the lock being shown in unlocked position;

Fig. 4 is a horizontal section through one side of the door opening on the line 4—4 in Fig. 1;

Fig. 5 is a vertical section through the door opening showing the position of the parts when the car is at the landing and the vertically sliding doors are partly open;

Fig. 6 is a view similar to Fig. 5 showing the positions of parts after the car has left the landing and the doors are closed;

Fig. 7 is a vertical section through the lock on the line 7—7 in Fig. 3; and

Fig. 8 is a view similar to Fig. 2 showing a modified form of locking device.

Referring to Figs. 1 to 7, inclusive, of the accompanying drawings, my invention is shown in connection with the shaft 10, car or cage 11, and the vertically sliding upper and lower door sections or gates 12 and 13 of an electrically operated freight elevator. As shown in the accompanying drawing, the upper and lower metal clad sliding door sections 12 and 13 for each door opening in the elevator shaft are provided along each vertical edge with an angle bar frame mem-

ber 14 slidably arranged between angle bar guides 15 that are rigidly secured to each other and to the adjacent jamb members 16 of the door opening. The upper and lower door sections are counterbalanced by means of chains 17 suitably connected to the lower corners of the upper door section 12. Said chains extend upwardly around pulleys (not shown) and are connected to the upper ends 60 of upright chain rods 18, whose lower ends are secured to the upper corners of the lower door section 13 by means of door arms 18^a that project horizontally therefrom.

The door is provided with a latching device comprising an operating lever 19, which is pivotally mounted for vertical swinging movement on the inner side of the lower door section 13 near the middle of its upper end portion, and oppositely extending horizontally slidably latch bars 20 and 20^a, whose inner ends are pivotally connected to the respective upper and lower arms of the operating lever. The free outer ends of the latch bars are adapted to be slidably supported on 70 the lower door section and slid beyond the side edges of said section into engagement with suitable catches provided therefor at the sides of the door opening when the upper or handle end of operating lever is 75 swung upwardly. One end of a coil spring 21 is attached to one of the latch bars and its other end is secured to a bracket 22 riveted to the inner surface of the lower door section, the parts being arranged so 80 that the spring tends to exert an outward pull on the latch bar and thus normally tends to hold the same in its latched position. The construction of elevator thus far described is well known and it is considered unnecessary to illustrate it in detail.

The outer end of the horizontally slidable latch bar 20 is provided at its upper edge with a notch 23, forming a hooked end portion adapted, in the latched position of the 95 latch bar, for cooperation with a locking device, which prevents unlocking of the door latching device when the elevator car is not at a landing and which also prevents the operation of the electric elevator until all 100 the doors in the elevator shaft are closed and locked. Said locking device comprises a hollow casing 24 which is bolted or otherwise rigidly secured to one of the angle bar door guides 15 in position to cooperate with 105 the notched outer end of the latch bar 20. The side of the casing which faces the

notched end of the latch bar 20 is provided with an opening 24^a adapted to receive the hooked end of said latch bar; and inner face of said casing is provided with an opening 5 which is closed by means of a removable cover plate 25. Pivotaly mounted in the lock casing for vertical swinging movement towards and away from the outer end of the latch bar 20 is an upright arm 26. The 10 lower end of said arm is journaled on a horizontal pivot 26^a fixed to said casing. Disposed between the inner edge of the arm 26 and a lug 27 on the casing is a coil spring 28 which operates to swing the upper end 15 of said arm in the direction of the latch bar 20. Rigidly secured to the inner or rear edge of the arm 26 of the lock is a fiber insulating block 29, which carries a pin 29^a upon whose outer end is sleeved a contact 20 plate 30. The contact plate 30, which forms one element of an electric switch, is held on the pin 29^a by means of a cotter pin 31; and a coil spring 32 is mounted on said pin between the insulating block 29 and said contact 25 plate 30. The contact plate 30, which forms one element of an electric switch, is held on the pin 29^a by means of a cotter pin 31; and a coil spring 32 is mounted on said pin between the insulating block 29 and said contact 30 plate 30. The contact members 33 are positioned in the casing so as to be engaged by the contact plate 30 when the arm 26 which carries said plate is swung rearwardly. Said contact members 33 are provided 35 with binding screws 33^a which receive the wires of an electric circuit (not shown) which controls the operation of the electric elevator.

Pivotaly mounted in a vertical slot provided therefor in the upper end of the arm 40 26 is a lever or catch 35 whose outer arm terminates in a downwardly projecting hook 36 adapted to interlock with the hooked outer end of the latch bar 20 in the projected or latched position thereof. The inner arm of the catch 35 is adapted to abut against the top wall of the opening 24^a in the casing when the latch bar is retracted and the arm 26 is pulled forward by said 45 bar, thus causing the hooked end of such catch to swing upwardly clear of the notch 23 in said bar after said hooked end has moved clear of said opening. When the arm 26 is swung rearwardly by the pressure of the latch bar 20 thereagainst, the catch 35 on the upper end of said arm is carried rearwardly through the slot 24^a in the lock casing, and the hooked end 36 of said catch abuts against the top wall of said slot and 50 is thus forced downwardly into interlocking engagement with the hooked outer end of said latch bar. Mounted on a shaft 37 journaled in the upper end of the lock casing at right angles to the horizontal pivot 55 for the arm 26 is a downwardly projecting

lock arm 38 adapted, in the rearward position of the arm 26, to swing in front of the upper end thereof and thus prevent forward swinging movement thereof. The rocker arm 38 is automatically swung into 70 position in front of the upper end of the arm 26 by means of a coil spring 38^a sleeved on the rock shaft with one end hooked over said rock arm and with the other end bearing against the top wall of the lock casing. 75

The rock shaft 37 projects beyond the rear side wall of the lock casing and has a release arm fixed thereto, said arm comprising a lower or inner section 39 fixed to rock shaft 37 and an upper or outer section 39^a adjustably secured to the outer end of the inner section and carrying a roller 40 at its outer end. The outer end of the release arm projects inwardly into the elevator shaft with its roller 40 disposed in the path of a cam plate 41 secured to the elevator car or cage 11. This cam is located so that it engages the roller 40 of the release arm when the car is at the landing, which action rotates the rock shaft 37 and causes the rock arm 38 fixed thereon to swing clear of the path of the arm 26.

The upper end of the arm 26 is provided with a pin 42 which projects rearwardly through a slot 43 provided therefor in the rear side wall of the lock casing. In the closed position of the locking device, said pin projects far enough beyond the lock casing to extend into the path of the upper arm of the lever 44 which is pivotally secured to rear side wall of the casing for vertical swinging movement at right angles to the axis of said pin. The lower arm of the lever 44 is counterweighted so as to cause the upper arm of said lever to swing into 105 the path of the arm 18^a; and said arm is held in a position opposite the pin 42 carried by the arm 26 by means of a stop lug 45 which is engaged by the counterweighted lower arm of said lever. In the closed position of the doors, the upper end of the counterweighted lever 44 is engaged by the door arm 18^a of the lower section, which arm operates to swing the upper arm of the lever 44 clear of the path of the pin 42 on the arm 110 26. When the door is opened, the arm 18^a of the lower section thereof moves downwardly clear of the upper arm of the counterweighted lever 44, whereupon said arm of said lever swings into a position opposite the 115 end of the pin 42 on the arm 26 and thus prevents said arm from being swung rearwardly to close the electric circuit which controls the operation of the elevator.

As shown in the drawing, the lower front 120 corner of the lock casing is provided with a beveled surface 46, which is engaged by the outer end of the latch bar 20 during the closing movement of the lower door section and causes said bar to slide inwardly against the 125

pressure of the spring 21. The latch bar is held in its retracted position by the lock casing until said bar reaches a position opposite the opening 24^a in the lock casing, in which position the hooked end of the bar is pushed into said opening into engagement with the arm 26. The outer end of the bar is supported for free sliding movement preferably by means of an anti-friction roller 47 journaled in the bracket 48 fixed to the inner side of the lower door section.

The operation of the device is as follows:

When the car arrives at a landing the cam fixed to the car engages the roller 40 at the outer end of the release lever and causes the rock arm 38 on the rock shaft 37 to swing clear of the upper end of the arm 26, which arm is prevented from outward swinging movement by the pressure exerted there-

against by the spring pressed latch bar 20. The operating lever 19 is then operated to cause the latch bar to slide inwardly against the pressure of the spring 21, which action, due to the interlocking engagement of the hooked ends of the latch bar and the catch 35 on the arm 26, causes said catch to travel outwardly through the opening 24^a in the lock casing. During the outward travel of the catch 35, the upwardly inclined inner arm thereof abuts against the lock casing and is forced downwardly, thereby causing the hook 36 on the outer arm of said catch to swing upwardly out of engagement with the hook at the outer end of the latch bar.

35 The counterweighted door sections are then separated by a downward pressure on the lower door section, which action causes the door arm 18^a at the upper corner of the lower section to move clear of the upper arm of the counterweighted stop lever 44 and thus permit said arm to swing in front of the pin 42 carried by the arm 26, thereby preventing rearward movement of the lever. This outward movement of the catch 35 causes the arm 26 which supports said catch to swing outwardly, which action breaks the contact between the contact plate 30 carried by said arm and the posts 33 mounted on the casing and thus opens the electric circuit 50 which controls the operation of the elevator.

When the doors are closed, the door arm 18^a swings the counterweighted lever 44 clear of the pin 42 on the arm 26, and the latch bar 20 is automatically slid into abutting relation with the said arm, in which position the notch 23 in said latch bar is directly beneath the hooked end 36 of the catch 35 carried by said arm. Further outward sliding movement of the latch bar forces the arm 26 to swing inwardly and carries the catch 35 thereon rearwardly into the opening 24^a in the lock casing. During the rearward travel of the catch 35 through the opening 24, the hooked outer end 36 of said catch abuts against the upper edge of said opening

and is swung downwardly into engagement with the hooked outer end of the latch bar. In this position of the catch 35, the pin 42 at the upper end of the catch supporting arm 26 swings in front of the counterweighted lock lever 44 and the contact plate 30 on the arm 26 bears against the contact members 33 mounted on the casing, thereby closing the electric circuit of the elevator and thus permitting the operation thereof.

The car may then leave the landing, whereupon the cam 41 thereon moves out of engagement with the roller 40 carried by the release lever and permits the shaft 37 to be rotated by the action of the spring 38^a and move the lock arm 38 into the path of the arm 26 and thus prevent unlocking of the elevator doors until the car again reaches the landing.

In the modified construction shown in Fig. 8, the counterweighted arm, which prevents tampering with the lock in the opened position thereof, and the parts actuated by the cam on the elevator to prevent unlocking of the parts until the elevator reaches the landing, are omitted. In this construction, the locks are attached to each door and are connected in series to the elevator controller board, so that the elevator cannot be operated until all doors in the shaft are closed and latched.

The hereinbefore described arrangement admits of considerable modification, and I do not wish to be limited to the precise arrangements shown and described.

What I claim is:

1. In an electric elevator, a shaft, a car working therein, doors for closing the door openings in said shaft, a latch bar for each door, a catch arranged to move into engagement with said latch bar when the same is moved to latched position, a switch for making and breaking an electric circuit for controlling the operation of the elevator car, means whereby said switch is automatically actuated to close the circuit in the engaged position of said latch bar and said catch and is automatically opened in the disengaged position thereof, and means releasable by the operation of opening the door for preventing the closing of said switch when the door is open.

2. In an electric elevator, a shaft, a car working therein, doors for closing the door openings in said shaft, a latch bar for each door, a catch arranged to move into engagement with said latch bar when the same is moved to latched position, a switch for making and breaking an electric circuit for controlling the operation of the elevator car, means whereby said switch is automatically actuated to close the circuit in the engaged position of said latch bar and said catch and is automatically opened in the disengaged position thereof, and means for pre-

venting the closing of said switch when the door is open

3. In an electric elevator, a shaft, a car working therein, doors for closing the door openings in said shaft, a latch bar for each door, a catch arranged to move into engagement with said latch bar when the same is moved to latched position, a switch for making and breaking an electric circuit for controlling the operation of the elevator car, means whereby said switch is automatically actuated to close the circuit in the engaged position of said latch bar and said catch and is automatically opened in the disengaged position thereof, means for preventing the closing of said switch when the door is open, and means releasable by the car at the landing for preventing disengagement of said catch from said latch bar after the car leaves said landing.

4. An electric elevator, a shaft, a car working therein, doors for closing the door openings in said shaft, a spring projected latch bar for each door, a lock casing secured to the shaft opposite the outer end of said latch bar, an electric switch mounted in said casing for making and breaking the electric current controlling the operation of the elevator car, an arm pivoted in said casing for swinging movement towards and away from said end of said latch bar, a catch pivotally mounted on the free end of said arm and adapted to move into interlocking engagement with said latch bar when the latter is pressed against said arm and swings it rearwardly, a spring for swinging said arm in the direction of said latch bar in the retracted position thereof, means whereby said latch is disengaged from said bar when said arm moves in said direction, and means operated by the swinging movement of said arm for closing said switch in the engaged position of said latch bar and said catch and for opening said switch in the disengaged position of said members

45. An electric elevator, a shaft, a car working therein, doors for closing the door openings in said shaft, a spring projected latch bar for each door, a lock casing secured to said shaft opposite the end of said latch bar and provided with an opening adapted to receive said end of said bar, an arm pivoted in said casing for swinging movement towards and away from said end of said latch bar, a catch mounted on said arm and adapted to move into engagement with said latch bar when the arm moves rearwardly under pressure of said bar, a spring for swinging said arm forwardly in the direction of said latch bar in the retracted position thereof, a switch for making and breaking the electric circuit controlling the operation of the elevator car, and means controlled by the swinging movement of said arm for closing said switch in the engaged

position of said catch and for opening said switch in the disengaged position of said catch.

6. An electric elevator, a shaft, a car working therein, doors for closing the door openings in said shaft, a spring projected latch bar for each door, a lock casing secured to said shaft opposite the end of said latch bar and provided with an opening adapted to receive said end of said bar, an arm pivoted in said casing for swinging movement towards and away from said end of said latch bar, a catch mounted on said arm and adapted to move into engagement with said latch bar when the arm moves rearwardly under pressure of said bar, a spring for swinging said arm forwardly in the direction of said latch bar in the retracted position thereof, a switch for making and breaking the electric circuit controlling the operation of the elevator car, means controlled by the swinging movement of said arm for closing said switch in the engaged position of said catch and for opening said switch in the disengaged position of said catch, and means for locking said catch and said switch in closed position, said locking means being adapted to be released by the car upon arrival thereof at the landing.

7. An electric elevator, a shaft, a car working therein, doors for closing the door openings in said shaft, a spring projected latch bar for each door, a lock casing secured to said shaft opposite the end of said latch bar and provided with an opening adapted to receive said end, an arm pivoted in said casing for swinging movement towards and away from said end of said latch bar, a spring normally tending to swing said arm in the direction of said latch bar, a catch mounted on said arm and adapted to move into engagement with said latch bar under pressure of the same against said arm, a switch for making and breaking the electric circuit controlling the operation of said elevator, and means operated by the swinging movement of said arm for opening said switch when the catch is disengaged from said latch bar and for closing said switch when the catch is engaged with said latch bar.

8. An electric elevator, a shaft, a car working therein, doors for closing the door openings in said shaft, a spring projected latch bar for each door, a lock casing secured to said shaft opposite the end of said latch bar and provided with an opening adapted to receive said end, an arm pivoted in said casing for swinging movement towards and away from said end of said latch bar, a spring normally tending to swing said arm in the direction of said latch bar, a catch mounted on said arm and adapted to move into engagement with said latch bar under pressure of the same against said arm,

means for automatically locking said arm and said catch against movement after the car leaves the landing, a switch for making and breaking the electric circuit controlling the operation of said elevator, means operated by the swinging movement of said arm for opening said switch when the catch is disengaged from said latch bar and for closing said switch when the catch is engaged with said latch bar, and means for preventing the closing of said switch when the door is open.

9. In an electric elevator, a shaft, a car working therein, doors for the door openings in said shaft, a horizontally slideable spring projected latch bar for each door, said latch bar having an upwardly opening notch at its outer end, a lock casing located opposite said end of said latch bar and having an opening adapted to receive the same, an arm pivoted in said casing for vertical swinging movement and adapted to be swung rearwardly under pressure of the latch bar thereagainst, a spring normally tending to force said arm towards said latch bar, a catch pivotally supported on said arm and having a hooked end adapted to engage the notch in said latch bar when the arm is swung rearwardly under pressure of said bar thereagainst, a switch adapted to make and break an electric circuit controlling the operation of the elevator car, said switch being adapted to be automatically closed when said arm is swung rearwardly under pressure of said latch bar thereagainst and automatically opened when said pressure is released, and means for locking said catch and arm against movement when the car leaves the landing.

40 10. In an electric elevator, a shaft, a car working therein, doors for the door openings in said shaft, a horizontally slideable spring projected latch bar for each door, said latch bar having a hook at its outer end, a lock casing located opposite said end of said latch bar and having an opening adapted to receive the same, an arm pivoted in said casing for vertical swinging movement and adapted to swing rearwardly under pressure of the latch bar thereagainst, a spring normally tending to force said arm toward said latch bar, a catch pivotally supported on said arm and having a hooked end adapted to interlock with the hooked end of said latch bar

when the arm is swung rearwardly under pressure of said bar thereagainst, means whereby said catch is automatically disengaged from said latch bar during the rearward movement thereof, a switch adapted to make and break an electric circuit controlling the operation of the elevator car, said switch being adapted to be automatically closed in the interlocked position of said catch and said latch bar and automatically opened before said members are disengaged, means for locking said catch and arm against movement when the car leaves the landing, and means for preventing the closing of said switch when the door is open.

11. In an electric elevator, a shaft, a car working therein, doors for the door openings in said shaft, a horizontally slideable spring projecting latch bar for each door, said latch bar having a roller for supporting the outer end portion of said bar, a hooked outer end, a lock casing located opposite said end of said latch bar and having an opening adapted to receive the same, an arm pivoted in said casing for vertical swinging movement and adapted to be swung rearwardly under pressure of the hooked end of latch bar thereagainst, a spring normally tending to force said arm toward said end of said latch bar, a catch pivotally supported on said arm and having a hooked end adapted to cooperate with the hooked end of said latch bar, means for swinging the hooked end of said catch into engagement with the hooked end of said latch bar when the arm supporting said catch is swung rearwardly under pressure of said bar thereagainst, means for disengaging the hooked ends of said catch and said bar when said arm is drawn forward by retraction of said bar, a switch adapted to make and break an electric current controlling the operation of the elevator car, means whereby said switch is automatically closed at the beginning of the closing movement of said catch and is opened at the beginning of the opening movement thereof, means for locking said catch and said switch in closed position when the car leaves the landing, and means for preventing the closing of said switch when the door is open.

Signed at St. Louis, Missouri, this 28th day of September, 1926.

JULIUS A. SCHWEIG.
